UNITED STATES PATENT OFFICE.

AUGUSTUS CARDIGAN FREDERICK DANN, OF SOUTHSEA, ENGLAND.

HYDRAULIC CLUTCH.

No. 893,455.

Specification of Letters Patent.

Patented July 14, 1908.

Application filed August 3, 1907. Serial No. 387,000.

To all whom it may concern:

Be it known that I, AUGUSTUS CARDIGAN FREDERICK DANN, a subject of the King of Great Britain, residing at 54 St. Augustine road, Southsea, in the county of Hants, England, engineer, have invented a certain new and useful Hydraulic Clutch, of which the following is a specification.

According to the present invention two shafts or the like are clutched to rotate coaxially at the same or at different speeds by varying the friction between one of the shafts or members and a mass or masses of fluid carried round by the rotation of the other member. The friction between the moving fluid and the member to be driven is arranged to be normally insufficient to overcome the resistance of the latter on no load, and the varied speed of the driven member is obtained by diminishing by suitable means the section of the path available for the movement of the fluid in the space between the driving and driven members. A continuous variation of this section produces a continuous variation of the slip or friction between the fluid and the driven member and consequently a continuous variation of the speed of the latter until, when the path is completely blocked, the two members are clutched absolutely and rotate at the same speed.

The invention is illustrated in the accompanying drawings in which

Figure 1 is a side elevation of the apparatus with a cheek plate removed and partly broken into section; Fig. 2 is a central longitudinal section; Figs. 3, 4, 5, and 6 views of various details hereinafter referred to.

As shown in these drawings, which are given by way of example only as showing the preferred embodiment of this invention, the fluid which correlates the two members and which is preferably an incompressible fluid, as for example a suitable lubricating oil, is inclosed in an annular space A formed between a shell B which constitutes or is secured to one of the members and a disk C which is mounted within and concentric with the shell B and rotates with the other member.

Pivoted within cavities in the internal periphery of the shell are pawls D which under the action of the oil, assisted or not by spring urged pistons d', are thrown into operative position when the shell is rotated, their front

surfaces d² blocking the annular passage A containing the fluid which is thus carried round with the shell. Mounted to slide in radial slots c' in the concentric disk C are blocks E which can be projected more or less towards the inner face of the rotating shell B thereby constricting the annulus at various points and consequently increasing the resistance to the passage of the fluid and the friction between the fluid and the disk. Radial holes or grooves e' are formed in the blocks to allow the displaced fluid to pass through to the inner side of the blocks when they are projected into the annulus A and a similar provision by means of holes d³ with or without leading grooves d⁴ is made to allow the passage of the fluid from the front face d² of the pawls to the rear face of the tail d⁵ of the pawls to assist the projection of the latter into the operative position and also to allow the fluid to pass from side to side when the pawls are rocked about their pivots as they pass over the projected blocks E. The radial blocks E are displaced in their guide slots c' by means of racks F which are slideable axially with respect to the disk and shell and which engage pinions f' formed on sleeves f² which are journaled radially in the disk C. Internal screw threads of considerable pitch in the pinion sleeves engage the correspondingly screwed inner ends of radial pins e², the outer ends of which carry the radial blocks E, the whole arrangement being such that when the racks are displaced axially the radial pins carrying the blocks are projected outwardly or retracted as the case may be.

The oil annulus A is isolated from the actuating gearing by means of annular cup leathers G or suitable equivalent packing fitted in grooves g' in the disk member C and forced under pressure of the oil against the cheek plates or sides H of the shell, and by suitable packing g² which closes the radial holes in the disks in which the radial arms or pins are mounted. Provision is also made for compensating for the increased volume of solid material projected into the oil space when the radial blocks E are moved outwardly, by providing collapsible chambers I adapted to yield under pressure so as to reduce the inclosed space and thereby provide additional oil space in rear of the radial blocks E. These collapsible chambers I are preferably constituted by a metal disk i

which fits snugly in a transverse hole extending through the disk C and has a central part cored out for lightness and filled with cork or like light material to reduce the air space. 5 On each face of the disk i is clamped a flexible composite spring plate or diaphragm i' of leather on its inner face and sheet metal on its outer face, which is clamped between the face of the disk and a metal ring i² by means 10 of set screws i³, a washer i⁴ of leather or other suitable soft material being interposed between the diaphragm i' and the ring i² to reduce any possible tendency of the diaphragm to fracture by repeated bending on 15 the edge of the ring. To enable the oil to pass to both sides of the disk C when the apparatus is being filled, small holes or grooves i⁵ are provided extending transversely across the disk C. 20 In the preferred construction shown in Figs. 3 and 5, the radial blocks are formed in two parts, the movement of the inner part E' being truly radial while that of the outer part E which is fulcrumed in the 25 disk C and connected with the inner part by a link such as e⁴, is a rocking movement about an axis parallel to that of the two members B, C, this construction securing an increased travel of the outer part E as compared with the inner part E'. The outer 30 surface of the rocking block is suitably shaped to guide the pawls gently from their normal position, and in order to reduce friction on the pawls during this part of their movement the surface of the rocking blocks E are preferably grooved or hollowed diagonally for part of their length as shown at e³ 35 from the point at which they engage the pawls so as to take the load off the pawls when traversing this portion by allowing the oil to slip underneath the nose of the pawl, the drive being taken by the pawl or pawls which are not then passing over the blocks E. It will be seen that the nose of the pawl 40 on leaving the surface of the rocking block gradually falls inwardly into the operative 45 position as its rearward part moves over the block. Further, in order that there may not be any actual solid friction between the 50 pawls and the surface of the disk member, the recesses b' in which the tails d⁵ of the pawls are accommodated are adapted also to act as stops to hold the nose of the pawl just out of actual metallic contact with the disk. 55 When the radial blocks E are thrust outwards to their limiting position against the shell B there will be no slip and the two members will rotate at the same speed. Provision 60 may be made for a mechanically locked drive under such condition by causing the same movement of the sleeve J, which is slotted at its end to form the racks F, to bring a clutch member j' fast on the sleeve into driving engagement with a clutch member j² 65 which is secured to the boss h' of the shell B.

The boss h' is also formed with a stuffing box and gland h⁰ within which the sleeve J slides. The sleeve J is keyed on the shaft J' by long feathers j³, the shaft, sleeve, disk C and the gear actuating the radial blocks E all rotating together. The end of the shaft J' is journaled in the closed outer boss h² of the shell B and this end of the shaft is preferably provided with a central bore hole j⁴ 70 extending inwardly from its end and transverse holes j⁵ radiating therefrom and preferably spirally disposed around the shaft for the purpose of allowing the escape of air from the interior of the boss h² when the racks F are thrust forward into the said boss, 75 the displaced air passing through a hole h³ connecting the interior of the boss with the outside. The sleeve J is actuated in the usual manner by means of a lever j⁶, and the axial movement of the sleeve in either direction is limited by means of a pin j⁷ screwed 80 in the sleeve and projecting into a slot j⁷ in the shaft J'. The clutch members j', j², when such are provided, are preferably arranged to come into driving engagement just 85 before the blocks E are projected quite into contact with the shell B. It will be apparent that when such a clutch is provided the shell B may be driven from the shaft J' as well as conversely, although only in the latter case will there be variability of speed of 90 the driven member. 95

Having thus described the nature of this invention and the best means I know of carrying the same into practical effect, I claim: 100

1. In an apparatus of the character herein referred to in which the driving and driven members inclose a fluid filled annulus, a block mounted on one of the members and adapted to slide thereon and to be projected to a varying extent into said annulus, a yielding stop on the second member projecting into said annulus and into the path of the block and means for operating said block from outside the apparatus; substantially as 110 described. 105

2. In an apparatus of the character herein referred to a driving and a driven member inclosing a fluid filled annulus, and a block mounted on one of the members and adapted to be projected to a varying extent into said annulus, said block being formed in two parts, one of which is movable radially while the other is pivoted at one end and connected with the radial part by a suitable link; substantially as described. 115

3. In an apparatus of the character herein referred to in which the driving and driven members inclose a fluid filled annulus, a block mounted on one of the members and adapted to slide thereon and to be projected to a varying extent into said annulus, means for operating said block from outside the apparatus and a pawl pivotally mounted on the other member and adapted to ride on the 120 125 130

surface of the former member so as to block said annulus; substantially as described.

4. In an apparatus of the character herein referred to, a pawl pivotally mounted on one member and adapted to ride on the surface of another member so as to block the space between the said members, and a stop on said pawl adapted to hold the nose of the pawl just out of metallic contact with the driven member; substantially as described.

5. In a fluid clutch of the character herein referred to a pawl pivotally mounted on one member and adapted to ride on the surface of another member so as to block the space between the said members, and a groove in said pawl adapted to allow the passage of fluid from side to side of said pawl, substantially as described.

6. In an apparatus of the character herein referred to comprising a driving and a driven member inclosing a fluid filled annulus, and a block mounted on one of the members and adapted to be projected into said annulus, a radial groove in said block adapted to allow the fluid to pass through the interior of the block when projected into the annulus and means for operating said block from outside the apparatus; substantially as described.

7. In an apparatus of the character herein referred to comprising a driving and a driven member inclosing a fluid filled annulus, and a block mounted on one of the members and adapted to be projected into said annulus, a radial groove in said block adapted to allow the fluid to pass through the interior of the block when projected into the annulus, a pawl pivotally mounted on one member so as to block the annulus and a diagonal groove on the surface of said block to facilitate the passage of the pawl when traversing said surface; substantially as described.

8. In an apparatus of the character herein referred to in which the driving and driven members inclose a fluid filled annulus, a plurality of blocks mounted on one of the members and adapted to slide thereon and to be projected to a varying extent into said annulus, a plurality of yielding stops on the second member projecting into said annulus and into the path of the blocks and means for

operating said blocks from outside the apparatus; substantially as described.

9. In an apparatus of the character herein referred to in which the driving and driven members inclose a fluid filled annulus, a plurality of blocks mounted on one of the members and adapted to slide thereon and to be projected to a varying extent into said annulus, means for operating said blocks from outside the apparatus and a plurality of pawls pivotally mounted on the other member and adapted to ride on the surface of the former member so as to block said annulus; substantially as described.

10. In an apparatus of the character herein referred to, a driving and a driven member inclosing a fluid filled annulus, a block mounted on one of the members and adapted to be projected to a varying extent into said annulus and means for automatically providing space for the fluid displaced by the projection of the block.

11. In an apparatus of the character herein referred to comprising a driving and a driven member inclosing a fluid-filled annulus and a block mounted on one of the members and adapted to be projected into said annulus, a collapsible chamber consisting of a metal disk, a flexible composite diaphragm clamped to the faces of said disk and adapted to yield to an increase of pressure caused by the variation in fluid space due to the displacement of said block; substantially as described.

12. In an apparatus of the character herein described, an outer member comprising a cylindrical shell with parallel cheek plates, an inner disk concentric therewith, and a U-shaped leather packing interposed between the said disk and cheek plates and subject to the pressure of the fluid between the outer and inner members; substantially as described.

In testimony whereof I have signed my name to this specification in the presence of two subscribing witnesses.

AUGUSTUS CARDIGAN FREDERICK DANN.
